UNITED STATES PATENT OFFICE.

GOTTLÖB WÖHR, OF NEW YORK, N. Y.

WINDMILL.

1,314,232.

Specification of Letters Patent. Patented Aug. 26, 1919.

Application filed December 10, 1918. Serial No. 266,116.

To all whom it may concern:

Be it known that I, GOTTLÖB WÖHR, a citizen of Germany, and resident of the borough of Manhattan, in the city and State of New York, have invented a new and useful Improvement in Windmills, of which the following is a specification.

One object of my invention is to provide a windmill in which the sails of the wind wheel are mounted to feather, so that they will swing into positions flatwise and edge-wise to the wind at opposite sides of the wheel.

A further object is to provide a yielding stop for the swinging movement of the sails so that when the wind becomes too strong the sails will swing sufficiently to spill the wind and if necessary will swing entirely past the stop to prevent the breaking of the parts, thus keeping the speed of the wheel automatically below the danger point.

A still further object is to provide a windmill of novel construction which will be very simple, strong and durable and in which the sails may be readily removed and replaced.

A practical embodiment of my invention is represented in the accompanying drawings, in which—

Figure 1 represents a windmill in top plan.

Fig. 2 represents the same in side elevation, the support being shown in vertical central section.

Fig. 3 is an enlarged detail view of one portion of the wheel.

Fig. 4 is a section taken in the plane of the line IV—IV of Fig. 3.

Fig. 5 is a section showing the relatively fixed cam of the yielding stop in top plan, and

Fig. 6 is a section showing the relatively movable cam in inverted plan.

The vertical shaft 1 is rotatably mounted in the support 2 of the windmill.

The wind wheel is mounted to rotate with the vertical shaft 1, and comprises the upper and lower hubs 3 and 4 from which project the pairs of upper and lower arms 5 and 6. In the present instance I have shown four pairs of these arms arranged at 90° apart. One or more vertical bars 7 connect each pair of upper and lower arms 6, in the present instance I have shown two such vertical bars 7 for each pair of upper and lower arms. Tie rods 8 connect the outer ends of

the upper arms 5 and tie rods 9 connect the outer ends of the lower arms 6.

To make a more rigid wheel diagonal tie rods 10 connect the upper arms 5 with a hub 11, fixed to the vertical shaft 1 a distance above the hub 3.

The sails 12 are hinged to swing about the vertical bars 7, each bar 7 has fixed thereon against relative movement upper and lower cams 13 and 14 which have steep inclines which co-act with steep inclines on upper and lower cams 15 and 16 rotatably and vertically movable on said bar 7. Upper and lower arms 17 and 18 project from the relatively movable cams 15 and 16 to which arms the top and bottom of the sail 12 is secured.

It is to be understood that the upper and lower cams 15 and 16 rest by gravity on the upper and lower cams 13 and 14.

For exerting additional pressure on the cams 15 and 16 I provide expansion springs 19 and 20, the expansion spring 19 being located between the top of the cam 15 and an adjusting nut 21. The spring 20 is interposed between the top of the cam 16 and an adjusting nut 22. The tension of the spring 19 and 20 may thus be adjusted to suit different requirements.

The cams are so arranged and formed that the sails 12 may have extended swinging movement around their vertical bars 7 without interruption and a further swinging movement under undue wind pressure. This further swinging movement is accomplished by permitting the steep inclines of the relatively movable cams to ride up on the steep inclines of the relatively fixed cams against the action of gravity and against the tension of the springs 19 and 20.

In operation under normal wind pressures, the sails 12 will present themselves flatwise to the wind at one side of the wheel, the sails being located substantially in the plane of their upper and lower arm 5 and 6. As the wheel revolves the sails are first thrown outwardly and then they present themselves edgewise to the wind as they reach a point upon the opposite side of the wheel. The sails will then gradually approach their position parallel with their upper and lower arms as they return to their first mentioned position. These different positions are indicated in Fig. 1 of the drawings.

If the wind pressure be too great the cams

which form the yielding stops for the sails will permit the sails to yield sufficiently to spill the wind and if necessary permit the sails to swing entirely past the stops thus serving to keep the speed of the wheel within the danger limits.

It is evident that various changes may be restored to, in the form, construction and arrangement of the several parts without departing from the spirit and scope of my invention, and hence I do not intend to be limited to the details herein shown and described, but

What I claim is:

15. 1. In a windmill, a horizontally rotating wind wheel having feathering sails arranged to swing into positions flatwise and edge-wise to the wind on opposite sides of the wheel and relatively fixed and movable cams which coact to stop the swinging movement of the sails except under undue wind pressure.
20. 2. In a windmill, a horizontally rotating wind wheel having feathering sails arranged to swing on vertical axes into positions flatwise and edge-wise to the wind on opposite

sides of the wheel, and relatively fixed and movable cams which coact to stop the swinging movement of the sails except under undue wind pressure.

3. In a windmill, a horizontally rotating wind wheel having vertical bars, cams fixed thereto, cams rotatably and vertically movable on said bars, sails carried by said last named cams, said fixed and movable cams coacting to limit the swinging movement of the sails except under undue wind pressure.

4. In a windmill, a horizontally rotating wind wheel having vertical bars, cams fixed thereto, cams rotatably and vertically movable on said bars, sails carried by said last named cams, said fixed and movable cams coacting to limit the swinging movement of the sails except under undue wind pressure, and means to adjust the amount of the resistance of the sails to said swinging movement under undue wind pressure.

In testimony, that I claim the foregoing as my invention, I have signed my name, this second day of December, 1918.

GOTTLÖB WÖHR.
